The ornamental design for an ultrasonic diagnosis apparatus, as shown and described.

DESCRIPTION

FIG. 1 is a front, top and right side perspective view of an ultrasonic diagnosis apparatus, showing my new design; FIG. 2 is a rear, top and left side perspective view thereof; FIG. 3 is a front view thereof; FIG. 4 is a rear view thereof; FIG. 5 is a left side view thereof; FIG. 6 is a right side view thereof; FIG. 7 is a top view thereof; FIG. 8 is a bottom view thereof; FIG. 9 is an enlarged fragmented front view of the ultrasonic diagnosis apparatus; taken along the two horizontal lines 9 of FIG. 3; and, FIG. 10 is an enlarged cross sectional view thereof; taken along the line 10-10 in FIG. 3. The broken lines showing in FIG. 3 are included to indicate the cutting plane of FIGS. 9 and 10. The broken lines of even length shown in the figures are for environmental purposes only and form no part of the claimed design.
